US00D835544S

(12) **United States Design Patent** (10) **Patent No.:** **US D835,544 S**
(45) **Date of Patent:** **** Dec. 11, 2018**

(54) **BALANCE SCOOTER**

(71) Applicant: **NINEBOT(BEIJING)TECH. CO., LTD**, Beijing (CN)

(72) Inventor: **Xiaoying Liu**, Beijing (CN)

(73) Assignee: **Ninebot (Beijing) Tech. Co., Ltd.**, Beijing (CN)

(**) Term: **15 Years**

(21) Appl. No.: **35/503,750**

(22) Filed: **Jul. 20, 2017**

(80) **Hague Agreement Data**

Int. Filing Date: **Jul. 20, 2017**

Int. Reg. No.: **DM/097802**

Int. Reg. Date: **Jul. 20, 2017**

Int. Reg. Pub. Date: **Oct. 6, 2017**

(30) **Foreign Application Priority Data**

Jul. 19, 2017 (CN) 2017 3 0321180

(51) **LOC (11) Cl.** **12-11**

(52) **U.S. Cl.**

USPC **D12/1**

(58) **Field of Classification Search**

USPC D12/1, 107, 109, 111-113

(57) **CLAIM**

The ornamental design for a balance scooter, as shown and described.

DESCRIPTION

1. Balance scooter

1.1 : Front

1.2 : Back

1.3 : Left

1.4 : Right

1.5 : Top

1.6 : Bottom

1.7 : Perspective

1 Claim, 7 Drawing Sheets
